UNITED STATES PATENT OFFICE.

WILLIAM C. HEINDL, OF ROCHESTER, NEW YORK.

PINWHEEL.

1,367,389.

Specification of Letters Patent. Patented Feb. 1, 1921.

Application filed December 8, 1919. Serial No. 343,356.

To all whom it may concern:

Be it known that I, WILLIAM C. HEINDL, citizen of the United States, residing at Rochester, in the county of Monroe and State 5 of New York, have invented certain new and useful Improvements in Pinwheels, of which the following is a specification.

The object of this invention is to provide a new and improved form of a double pin 10 wheel made of two sections in such a manner that the blades of the sections are evenly spaced apart, the sections being interlocked together.

This and other objects of the invention 15 will be fully illustrated in the drawings, described in the specification and pointed out in the claims at the end thereof.

In the accompanying drawings:

Figure 1 is a plan view of the front section 20 of the double pin wheel.

Fig. 2 is a plan view of the rear section of the double pin wheel.

Fig. 3 is a plan view of the front and rear sections of the double pin wheel as they 25 appear when placed one on top of the other with their outer edges lined up parallel to one another.

Fig. 4 is a plan view of the front and rear sections of the double pin wheel as they appear 30 when one is placed on top of the other and one of the sections has been shifted relative to the other to nest the wings of one section between the wings of the other section and interlock the sections.

Fig. 5 is an elevation of the double pin 35 wheel formed by bending the right hand tip of each wing of the two sections to the center.

In the drawings, like reference numerals indicate like parts.

In the drawings, reference numeral 1 indicates 40 a plan view of the front section and reference numeral 2 indicates a plan view of the rear section of the pin wheel. Each of these sections is made of a square piece of 45 stock which is sufficiently stiff yet flexible enough to keep its shape when bent to the desired form. From each quarter of each of these sections a slit is cut extending radially toward the center for a suitable distance.

The slit at the inner end curves around in 50 a uniform direction to terminal points located eccentrically $22\frac{1}{2}^{\circ}$ to one side of radial lines drawn from the corners of said sections, from which terminal points a comparatively short slit extends outwardly at 55 an angle to the long slit. It is shown in

both sections because both sections will be made with the same die. In one of the sections this short slit will not function and it may be omitted from that section on that account. The sections are otherwise the same, the only difference in the front and rear sections being a difference in position. The rear section is reversed or inverted in its position as compared with the position of the front section. This reversion of position causes the curved part of the slit to bend in the opposite direction. This is necessary to secure the proper engagement of the wings and interlocking effect between the sections.

The wings of the front section are indicated by the reference numerals 3, 4, 5 and 6 and the wings of the rear section are indicated by the reference numerals 7, 8, 9 and 10.

For the purpose of forming a pin wheel, the front section is laid on top of the rear section and the left hand corner of each wing of the rear section is lifted and the front section is then rotated so that the right hand rear corner of each wing thereof will pass under the left hand corner of the wing ahead of it on the lower section, as it is rotated, causing the right hand end of each wing of the front section to be nested between the adjacent ends of the adjacent wings of the rear section. The front section is rotated in this way about 45° keeping the center of the sections in line with each other. This will bring the ends of the curved slots in the one section into engagement with the ends of the curved slots in the other section, at which point the offsets in the slots of one section can engage with the wings of the other section, causing the one section to be positively interlocked with the other section.

The right hand end of each wing can then be turned in to the center and the corners thus brought to the center can be fastened together with a single pin which will pass through the center of the two sections and will hold the sections together as a wheel revolving thereon as on an axis.

By making the front section of a material of one color and making the other section of a material of another color, a combination of color effects may be secured.

By cutting the sections and putting them together in this way, the sections are not only interlocked but an even or uniform

spacing of the wings is secured, and the left hand edges of the wings are all held radial to the center.

It will be understood that the inner end 5 of the slit may be either curved or bent at an angle so that the slit will be in two straight lines instead of a straight line and a curve, the bent or curved portion in each case being in addition to the offset at the end 10 thereof. In either case, when one of the sections is reversed and nested and interlocked with the other section, the slits in the two sections will stand about 45° apart.

I claim:

- 15 1. In a double pin wheel, the combination of a pair of polygonal sections, one superimposed on the other, each of said sections being slit at their corners with diagonal or radial slits to form a series of wing members out of each of said sections, the diagonal slits having their inner ends curved outwardly and terminating in short slits forming extensions at an angle to said diagonal slits, the slots of one section being curved in the direction opposite to those of the other section and the wing members of one section nesting between the wing members of the other section in such a manner that the wing members 30 of one section project into the angular extensions of the slits of the other section, one corner of each wing member being bent to the center and fastened on the axis of the wheel.
- 35 2. In a double pin wheel, the combination of a pair of polygonal sections, one superimposed on the other, each of said sections being slit at their corners with diagonal or radial slits to form a series of wing members out of each of said sections, the diagonal slits having their inner ends curved outwardly, the slits in one section terminating each in short slits forming extensions at an angle to said diagonal slits, one section being placed on the other section with its slits curved in the opposite direction to the lower section, the wing members of one section nesting between the wing members of the other section in such a manner that 45 50 the wing members of one section project into the angular extensions of the slits of the other section and are held in locked engage-

ment thereby, one corner of each wing member being bent to the center and fastened on the axis of the wheel.

55

3. In a double pin wheel, the combination of a pair of polygonal sections, one superimposed on the other, each of said sections being slit at their corners with diagonal or radial slits to form a series of wing members out of each of said sections, means for holding one of said sections in locked engagement with the other section with the projecting tips of the two sections spaced substantially uniformly apart in a circle, 60 one corner of each wing member being bent to the center and fastened on the axis of the wheel.

60

4. In a double pin wheel, the combination of a pair of polygonal sections, one superimposed on the other, each of said sections being slit at their corners with diagonal or radial slits to form a series of wing members out of each of said sections, the diagonal slits having their inner ends curved outwardly, one section being placed on the other section with its slits curved in the opposite direction to the lower section, the wing members of one section nesting between the wing members of the other section, one corner of each wing member being bent to the center and fastened on the axis of the wheel.

70

5. In a double pin wheel, the combination of a pair of polygonal sections, one superimposed on the other, each of said sections being slit at their corners with diagonal slits to form a series of wing members out of each of said sections, said diagonal slits terminating at points $22\frac{1}{2}^\circ$ to one side of 85 radial lines drawn from the corners, one of said sections having short slits extending outwardly from said terminal points, the wing members of one section being adapted to nest between the wing members of the other section in such a manner that the wing members of one section project into the angular extension slits of the other section, one corner of each wing member being bent to the center and fastened on the axis of the 90 wheel.
